UNITED STATES PATENT OFFICE.

JOSEPH HEGINBOTHOM, OF PHILADELPHIA, PENNSYLVANIA.

TUNING-PIN.

No. 903,086.

Specification of Letters Patent.

Patented Nov. 3, 1908.

Application filed July 22, 1908. Serial No. 444,855.

To all whom it may concern:

Be it known that I, JOSEPH HEGINBOTHOM, a citizen of the United States, residing in Philadelphia, Pennsylvania, have invented 5 certain improvements in Tuning - Pins, of which the following is a specification.

The object of my invention is to so construct a tuning pin for pianos, harps, and like stringed musical instruments as to prevent 10 loosening of the pin due to the shrinking of the wood of which the pin-block or like pin-receiving member of the instrument is usually composed. This object I attain in the manner hereinafter set forth, reference being 15 had to the accompanying drawing, in which

Figure 1 represents a side elevation, on an enlarged scale, of a tuning pin constructed in accordance with my invention, and Fig. 2 represents another form of tuning pin also 20 embodying my invention.

The ordinary tuning pin of a piano is a solid pin of iron or steel of uniform diameter throughout except as to the tapered point and squared and tapered head, the pin being 25 threaded externally throughout the greater portion of its length and being screwed into an opening in the pin-block of the piano. As the thread cut upon the pin is usually very fine the slightest shrinkage in the wood of the 30 pin-block permits the pin to back off, thereby letting down the tension upon the wire which it controls and putting said wire out of tune. In order to overcome this objection I provide the tuning pin with a central vertical slot 1, 35 thereby dividing the threaded portion of the pin into opposite resilient members 2, 2, whereby, when the pin is screwed into the pin-block, the threaded members will be forced together and the slot will be closed or 40 partially closed, each member, therefore, having a constant tendency to spring outward and resume its normal position, which tendency causes it to follow any expansion in diameter of the opening in the pin-block due 45 to shrinkage of the wood of which the same is composed, the result being that the threads of the pin are kept in close engagement with the threads on the interior of the opening in the pin-block and the backing off 50 of the pin by the strain of the wire thereupon is prevented.

In order to increase the outward thrust of the side members of the pin, each of the same is slightly swelled or expanded between its 55 upper and lower ends as shown in Fig. 1, the

greatest swell being preferably about midway of the threaded portion of the pin, because, when thus located, contact of the two members of the pin, when external pressure is applied thereto, begins at the lower end or point 60 of the pin and gradually proceeds upwardly until the point of greatest expansion is reached, and this insures the best hold of the pin upon the pin-block without detracting from the desired elasticity of the members of 65 the pin, which implies the extension of the slot therein for some distance above the point of maximum swell or expansion.

The pin is, by preference, first threaded, then slotted and then spread or expanded so 70 as to impart a like spread or expansion to the slot, as shown in Fig. 1, but the swell or expansion of the members of the pin may be due to the initial conformation of the same, the slot being of uniform width throughout 75 as shown in Fig. 2. The swell or expansion may be limited to one member of the pin if desired, although it is preferable to swell or expand both members of the pin in the manner described. 80

I am aware that an ordinary tapered wooden tuning pin or peg has been slotted longitudinally and the slot filled with rubber or other elastic material, but my invention differs from that referred to, in that the pin 85 is of metal, is externally threaded, and is without any distending agency other than the resiliency of the members of the pin, moreover, the prior tuning pin or peg referred to lacked the swell or expansion of the side 90 members of the same which is an important feature of my invention.

I claim:

1. A metal tuning pin threaded externally and having a central longitudinal slot, 95 whereby the pin presents opposite resilient members.

2. A metal tuning pin threaded externally, slotted longitudinally, and having a lateral swell in either of the members thus 100 formed.

3. A metal tuning pin, threaded externally, slotted longitudinally, and having a lateral swell in each of the members thus 105 formed.

4. A metal tuning pin, threaded externally, slotted longitudinally, and having a lateral swell in either of the members of the pin thus formed, as well as in the slot.

5. A metal tuning pin, threaded exter- 110

nally, slotted longitudinally, and having a lateral swell in each of the members of the pin thus formed, as well as in the slot.

6. A metal tuning pin threaded externally, slotted longitudinally, and having, in either of the members of the pin thereby formed, a lateral swell which is greatest about midway of the length of the slot.

7. A metal tuning pin threaded externally, slotted longitudinally, and having, in each of the members of the pin thereby formed, a lateral swell which is greatest about midway of the length of the slot.

8. A metal tuning pin threaded externally, slotted longitudinally, and having, in

said slot and in either member of the pin, a lateral swell which is greatest about midway of the length of the slot.

9. A metal tuning pin threaded externally slotted longitudinally, and having, in said slot and in each member of the pin, a lateral swell which is greatest about midway of the length of the slot.

In testimony whereof, I have signed my name to this specification, in the presence of 25 two subscribing witnesses.

JOSEPH HEGINBOTHOM.
